UNITED STATES PATENT OFFICE.

LOUIS GIRARD, OF MANVILLE, RHODE ISLAND.

LOOM.

1,152,311.

Specification of Letters Patent. Patented Aug. 31, 1915.

Application filed May 9, 1914. Serial No. 837,441.

To all whom it may concern:

Be it known that I, LOUIS GIRARD, citizen of the United States, residing at Manville, in the county of Providence and State of Rhode Island, have invented new and useful Improvements in Looms, of which the following is a specification.

My present invention pertains to looms and more particularly to means for raising 10 and lowering the swivel board of a loom and the elements carried by the same.

The object of the invention is to so equip a loom as to bring about the weaving of fancy cotton fabrics such as those having 15 spots, and this with the provision of a single controlling element in the pattern operating chain or card, as against the old method in which it is essential to employ at least two elements in the pattern-operating chain or 20 card to operate the swivel board and the picker-stick connections, respectively.

With the foregoing in mind, the invention in all of its details will be fully understood from the following description and claims 25 when the same are read in connection with the drawings, accompanying and forming part of this specification, in which:

Figure 1 is a side view, partly in section, of so much of a loom as is necessary to illustrate the preferred embodiment of my invention. Fig. 2 is a side detail view, on an enlarged scale, showing my novel mechanism. Fig. 3 is a view of the same, taken at a right angle to Fig. 2. Fig. 4 is a side 35 view, partly in section, showing one of the swivels of which there may be any number employed. Fig. 5 is a rear view of the same.

Similar numerals of reference designate corresponding parts in all of the views of 40 the drawings.

The loom frame 1 may be and preferably is of the ordinary construction, and in the same is arranged the main or crank shaft 2, and the cam shaft 3 which operates the 45 picker stick and the shuttle. On the frame 1 is the breast beam 4, and connected through standards 5 with frame 1 is the lay 6.

At 7 is the driving link between the lay 6 and the shaft 2, while at 8 is the reed, at 8^a the harnesses, and at 9 the finished cloth, 10—10, Figs. 1, 4 and 5 being the warp threads.

11 indicates the swivel board, and 12 the swivel, but one swivel being shown, though 55 it is to be understood that the swivel board

is to carry a number of the same as before mentioned.

On the shaft 2 is a driving gear 13, and on the shaft 3 is a driven gear 14, said driven gear being twice as large in diameter as the gear 13 so as to rotate slower than the same.

Suitably secured as by the nut and washer 20 and 21 on the shaft 2 is a sleeve 22 having a flange 23 at its inner end, the sleeve excepting the flange being of angular form in 65 cross-section. On said angular portion and abutting against the flange 23 is a disk cam 24, detachably secured to the sleeve. This cam has a recess 25 in its periphery as indicated by the dotted lines in Fig. 3. Slidable 70 on the angular sleeve 22 is a disk 26, corresponding in diameter with the unrecessed portion of the cam disk 24. On the outer side of the disk 26 is a hub 27, circumferentially grooved at 28 for the engagement of 75 the bifurcated portion 29 of an arm 30 through the medium of which the disk 26 is movable on the sleeve 22 in the direction of the length thereof.

At 30^a is a shaft on which is an arm 31, 80 equipped with an anti-friction roller 32, disposed at its outer end. The said roller 32 is designed to bear against and rotate on the cam-disk 24 and also on the disk 26 when the latter is moved inwardly into proper position for the purpose. As shown in Fig. 2, the disk 26 is idle, and therefore the roller 32 is free to follow the irregularities of the perimeter of the cam disk 24, with a view to raising and lowering the arm 31 and rocking 85 the shaft 30^a about its axis, and actuating the rods 35 and 36; the rod 35 being connected to a second arm 35^a on the shaft 30^a, and the rod 36 being connected with the shaft 30^a through a depending arm 37 on 90 said shaft. The rod 35, Fig. 1, is connected to an operating lever 40, and by this lever the swivel board 11 is moved upwardly and downwardly through a connecting rod 41, this rod being arranged clear of the path of 95 the shuttle so as not to interfere with the movements of the same.

The swivel board 11 is preferably mounted on the lay and the operating lever 40 is preferably connected with said swivel board 105 in the same manner as the lever H disclosed in the patent to Borton Number 467,272 of Jan. 19, 1892.

The swivel board 11 is shown by full lines in Fig. 1, as in its raised and idle position, 110

and to place said board in operative position the same is lowered as shown by dotted lines in said figure. Through the operating means in the swivel board, the swivel is caused to rotate about the upper warp threads 10 to make the patterns desired; the swivels and the swivel board *per se* being well known in the art, and not being of my invention.

10 In the manufacture of fancy cloth such as hereinbefore alluded to, when spots or other designs are to be made, by means of the pattern controlling parts, the necessary warp threads 10 are raised by the harnesses 8^a, and 15 through the necessary connections with the arm 30 the disk 26 is placed as shown in Fig. 2 which enables the roller 32 to operate as before described under the control of the disk 24. Raising of the arm 35^a will be attended by lowering of the swivel board 11 and the operating parts that it carries. The arm 37 at this time swings to the left, which through proper connections places the picker stick and the shuttle out of operation. 20 Incidental to the operations just described, the swivel board, the swivel and the raised warp threads 10 occupy the relative positions shown in Figs. 4 and 5, and thereupon the swivels by operating means, forming no 25 part of this invention, are rotated about the threads, and in that way the spots or patterns in the fabric are produced. When the production of the patterns is completed, the pattern mechanism causes the arm 30 to 30 slide the disk 26 toward the left, Fig. 2. This will prevent the roller 32 from dropping into the peripheral recess of the cam 24, and then the plain weaving by the shuttle will be resumed; the swivel board and 35 the parts thereof remaining out of operative 40 position.

The arm 30 may be and preferably is hinged at its lower end and may be pulled toward the left in Fig. 2, against the action of a spring, through the medium of a cable interposed between the arm and a jacquard or other suitable controlling mechanism, for instance in the manner disclosed by the patent to Kennedy, Number 512,474 45 of Jan. 9, 1894.

In lieu of placing the cam disk 24 on the shaft 2, said disk and its companion parts may be arranged on the slower shaft 3 to produce the result desired, in which event

because of the comparative slowness of the shaft 3 the cam disk 24 would be provided with two peripheral recesses like the recess 25, said recesses being opposite each other with their ends equi-distant.

It is to be understood that my invention 60 resides in the means best shown in Figs. 2 and 3 for putting the swivel board and its appurtenances into and out of operation, and for this reason I have deemed it unnecessary to illustrate in detail the conventional parts of the loom.

Having described my invention, what I claim and desire to secure by Letters-Patent, is:

1. In a loom, the combination of one of 70 the working shafts of a loom, a cam disk fast thereon and having a recessed periphery, a disk movable laterally on the shaft, at one side of the cam disk, and having a regular circular periphery, means for moving 75 the last-named disk toward and from the cam-disk, and a lever having connections for moving a swivel board; said lever being movable by the cam-disk when the second-named disk is out of engagement with 80 the lever, and being held against movement by the cam-disk when the second-named disk is positioned close to the cam-disk and is in engagement with the lever.

2. In a loom, the combination of one of 85 the working shafts of a loom, a cam disk fast thereon and having a recessed periphery, a disk movable laterally on the shaft, at one side of the cam disk, and having a regular circular periphery and also having 90 a circumferentially grooved portion, a bifurcated arm straddling said grooved portion and adapted when actuated to move the second-named disk laterally, and a lever having 95 connections for moving a swivel board; said lever being disposed at right angles to the disks and being provided with an anti-friction roller for the engagement of the disks, substantially as and for the purpose set forth.

In testimony whereof I have hereunto set my hand in presence of two subscribing witnesses.

LOUIS GIRARD.
